CLEANER FOR FORKS, COMBS, OR LIKE IMPLEMENTS

Filed April 4, 1947

UNITED STATES PATENT OFFICE

2,501,208

CLEANER FOR FORKS, COMBS, OR LIKE
IMPLEMENT

Sidney Cheldin, Santa Monica, Calif.

Application April 4, 1947, Serial No. 739,406

3 Claims. (Cl. 15—104)

1

This invention has to do with a cleaner for forks, combs, or like implements, and with a method of making such a cleaner, it being a general object of the invention to provide a cleaner or cleaning device that is simple and effective.

Toothed implements such as forks and combs become dirty; that is, foreign matter lodges between the teeth and it becomes difficult to remove such foreign matter. In many instances foreign matter lodges in such implements so that it is not removed by ordinary washing or cleaning operations and in the case of forks used to handle food this is a disagreeable and unsatisfactory condition.

A general object of my present invention is to provide a cleaner for toothed instruments such as forks or combs, which cleaner is of simple, inexpensive construction and is formed so that it can be readily cleaned or washed so that it can be kept in satisfactory condition for use.

Another object of the present invention is to provide a simplified and improved cleaner construction relating the ends of the cleaner to the body which is formed of separate strands. By my present invention the end portions of the strands extend transversely into the ends of the cleaner where they are secured by longitudinal ties, the ties and end portions being woven together.

A further object of the present invention is to provide a cleaner constructed in the manner hereinabove indicated wherein the woven parts may be held rigid and set against unraveling or separation by adhesion.

Another object of the present invention is to provide a simplified, practical, and easily manufactured mounting means by which the cleaner can be attached to a hook or suspended from a suitable object for storage or use. In accordance with my invention the mounting means involves a looped part or member projecting from one of the ends of the cleaner midway between its ends and in the preferred form of the invention the looped member is an extension or continuation of an elongate part forming strands of the cleaner body.

The various objects and features of my invention will be fully understood from the following description of typical preferred forms and applications of the invention, throughout which description reference is made to the accompanying drawings, in which:

Fig. 1 is a view illustrating a typical form or embodiment of the present invention. Fig. 2

2

is an enlarged detailed transverse sectional view taken as indicated by line 2—2 on Fig. 1. Fig. 3 is an enlarged view of the upper portion of the cleaner showing the details thereof and showing the strands of the body somewhat parted to illustrate the fact that they are separate or independent of each other, and Fig. 4 is an elongate strip as initially woven and embodying a plurality of cleaners joined end to end ready for separation into individual cleaners.

The device of the present invention is useful, generally, as a cleaner for toothed implements such as combs or forks and in the drawings I have shown a form of the invention particularly suited for the cleaning of forks such as are used in the kitchen or dining room for the handling of food, since it is particularly important that such implements be cleaned occasionally to remove foreign matter that is not dislodged by ordinary washing. Furthermore, the form of the invention illustrated in the drawings can be used to advantage in the polishing of silverware and particularly forks, where it is difficult to polish between the prongs or teeth and where polishing materials of some characters have a tendency to lodge and become difficult of removal.

The cleaner illustrated in the drawings involves, generally, two elongate spaced parallel ends A with a body B of strands extending between the ends and with a mounting means C projecting from one of the ends. The device may be formed of a fibrous material such as cotton, or the like, so that it can be readily washed or otherwise cleaned to keep it in condition for use.

The ends A may be formed of the same material or materials as the body B and the mounting means C except that at these parts the material is so formed, for instance woven, as to have substantial body and to be more or less rigid in order to give the desired support to the body B. The body B of the cleaner is a stranded element, that is, it involves a plurality of independent or separate strands 10 which extend freely from one end A to the other, at which points the strands are anchored. In the preferred form of the invention the several strands 10 are of corresponding size and shape and they are preferably in the form of strings or cords wrapped or twisted to have the desired size and body and yet be soft enough to flex and be operable between the tines or prongs of the implement to be cleaned.

Since I preferably form the entire cleaner of cord, or the like, the strands 10 are preferably in the nature of a heavy cotton string or cord.

Each end A of the cleaner is integrally joined with the body B by providing the strands 10 with end continuations 11 which are woven into and become part of the end. In the preferred form of the invention each strand 10 has an end continuation or an end portion 11 extending transversely of the end A and the several end portions 11 of the strands are bound or tied together by ties 12 that extend longitudinally of the end and which are preferably woven to or with the end portions 11 in the manner illustrated throughout the drawings. In carrying out my invention I may stitch, weave, or otherwise unite the ties 12 with the end portions 11 of the strands 10 to form an end A which is tight and of sufficient body and mass as to be substantially rigid in order to effectively hold the end portion of the body B in the desired form or shape as shown throughout the drawings.

It is a feature of my invention that I provide an effective cleaner without employing metal parts in the form of metal frames, holders, or reinforcements, and in lieu of such parts I make the ends A sufficiently tight and of sufficient body to give the cleaner the desired form or shape.

A further feature of my present invention is the formation of the strands 10 of body B and the portions 11 of the ends A from a single continuous length of material; for instance, a single string or cord, in which case the length of cord is in a zig-zag form or shape extending back and forth from one end A to the other, being bent or turned back on itself at points X as clearly illustrated throughout the drawings.

The mounting means C that I have shown in the drawings is preferably confined to one end A of the structure; however, I may apply a mounting means to both ends A if I so desire. The mounting means projects from the end A preferably so that it coincides with the central axis of the structure, as clearly illustrated in Fig. 1 of the drawings. The mounting means C is preferably in the form of a length of material looped as shown in Fig. 1, and it is preferably formed by continuing the string or cord employed in forming the cleaner beyond the edge of end A so that it is folded or bent back upon itself at Y which is remote from the end A rather than being bent back at a point X occurring at the edge of the end A, as are all other parts of the cord employed in the body. It will be apparent from the drawings that in following my construction the end portions of the string or cord are bent back or looped at X along the outer edge of the end A at all points except where the mounting means C occurs, and at that point the string is extended to project from the outer edge of end A enough to form the loop of the means C.

I may, in carrying out my invention, so form the ends A that the parts or materials entering into them are bonded or united to remain together, substantially rigid and in shape. Further, the parts entering into the ends are so related that they will not unravel. However, when I employ a simple weave, as illustrated in the drawings, it is desirable that the parts be held together by adhesion to provide rigidity and to prevent unraveling. In the form of the invention illustrated I may apply a binder to the end parts A of the holder, or I may employ ties 12 of a plastic material which when subjected to heat or other suitable treatment will fuse together so that the entire structure remains rigid and intact. In accordance with my invention I may employ any suitable material as the binder; for instance, a

body of thermo plastic material, or any suitable insoluble adhesive can be used. By insoluble I refer to an adhesive insoluble in the usual mediums employed for washing an article such as the cleaner that I have described. When employing a tie of plastic material any suitable plastic may be used that will not be effected by the usual temperatures or mediums employed for washing. In practice a wide variety of so-called plastic materials soluble in special solutions or workable under high temperatures may be used to advantage.

In carrying out the method of my invention, I weave an elongate strip such as is shown in Fig. 4, incorporating a plurality of cleaners joined edge to edge in a single continuous body. In performing the weaving operation I handle the length of string or cord that is to form the strands 10 and portions 11 so that it is laid back and forth, turning or bending it upon itself at points X and at suitable intervals extending it to form the means C in which case it is bent back upon itself at Y. If a binding material is to be used it is applied to the ends A, or if the ties 12 are of a plastic material, suitable heat is applied in a proper manner to fuse those parts together and to bond them to other parts with which they are woven or are in contact. The final operation in the manufacture is severing the end forming parts where the bodies of binding material occur, as for instance along the line indicated at Z in Fig. 4, which severing operations part the initially formed strip, dividing it into separate or individual cleaners such as are shown in Fig. 1.

From the foregoing description it will be apparent that I have, by my present invention, provided a cleaner that is effective in form and extremely simple and inexpensive of manufacture. Through the method of manufacture cleaners can be made automatically, or in a machine, so that they are formed rapidly and cheaply in a continuous strip to be thereafter separated or parted into the individual cleaners by a very simple parting or cutting operation.

Having described only typical forms of apparatus and manners of carrying out the method of my invention, I do not wish to be limited or restricted to the specific details herein set forth, but wish to reserve to myself any variations or modifications that may appear to those skilled in the art and fall within the scope of the following claims.

Having described my invention, I claim:

1. A cleaner of the character described including, an elongate body comprising a plurality of separate flexible strands extending from one end of the body to the other and being normally substantially parallel with each other, end parts at the ends of the body extending transversely of the body and having the said strands anchored thereto, and mounting means including a loop member attached to one of said end parts, each end part including extensions of the said strands and ties woven to said extensions and extending transversely thereof, the loop member being continuous with extensions of the strands.

2. A cleaner of the character described including, a unit having an elongate body and end parts extending transversely of the body at the ends thereof, and a mounting member carried by and projecting from one of the end parts, the body and end parts being formed by a length of flexible material folded back upon itself at each end of the cleaner with strand portions extending longitudinally of the body and with extensions

of the strand portions at the end parts, and ties extending in a direction transverse of the body and woven to said extensions of the strands.

3. A cleaner of the character described including, a unit having an elongate body and end parts extending transversely of the body at the ends thereof, and a mounting member carried by and projecting from one of the end parts, the body and end parts being formed by a length of flexible material folded back upon itself at each 10 end of the cleaner with strand portions extending longitudinally of the body and with extensions of the strand portions at the end parts, and ties extending in a direction transverse of the body and joined to said extensions of the strands, the mounting member being a length of said material continuing from extensions of the strands that occur at one of the end parts.
